SURGICAL SAW

Samuel Lloyd Fisher, Brooklyn, N. Y.

Application June 11, 1938, Serial No. 213,115

10 Claims. (Cl. 128—317)

This invention relates to surgical instruments in general and more especially to devices used in the medical profession in the treatment of bone fractures and the like.

Among the objects of the present invention, it is aimed to provide an improved portable combination motor and surgical instrument holder from which the motor can be easily removed to facilitate sterilization and the like.

It is still another object of the present invention to provide an improved combination motor and tool holder suitable for receiving an attachment for operating a drill, Kirschner wire, saw or the like surgical instrument.

It is still another object of the present invention to provide an improved supporting guide for a Kirschner wire while being operated and the like.

It is also an object of the present invention to provide an improved combination shell and motor which can be operatively connected with a high speed surgical drill, saw or the like or with a low speed router screw or the like without interfering with any of the attributes essential to a surgical instrument that can be readily sterilized and satisfactorily retained in its sterilized condition.

These and other features, capabilities and advantages of the invention will appear from the subjoined detail description of one specific embodiment thereof illustrated in the accompanying drawings in which

Figure 1 is a longitudinal section of a combined motor and tool holder equipped with a rotary saw made according to the present invention;

Fig. 2 is a section on the line 2—2 of Fig. 1;

Fig. 3 is a section similar to the section of Fig. 2 but with one of the saws removed and a protecting cap attached in place;

Fig. 4 is a section on the line 4—4 of Fig. 3;

Fig. 5 is a rear elevation on a small scale of the motor containing shell illustrated in Fig. 1;

Fig. 6 is a section on the line 6—6 of Fig. 1;

Fig. 7 is a diagrammatic view on the line 7—7 of Fig. 1;

Fig. 8 is a perspective of the operating switch detached from its associated parts;

Fig. 9 is a longitudinal section of an auxiliary shell with a reduction associated therewith and a screw holding attachment in operative association with the shell illustrated in Fig. 1;

Fig. 10 is an elevation showing two bone portions connected by a screw and the screw holder after having been removed from the screw;

Fig. 11 is a section on the line 11—11 of Fig. 10;

Fig. 12 is a section on the line 12—12 of Fig. 9;

Fig. 13 is a section on the line 13—13 of Fig. 12;

Fig. 14 is a longitudinal section of a Kirschner wire operating attachment connected to the shell shown in Fig. 1;

Fig. 15 is a section on the line 15—15 of Fig. 14;

Fig. 16 is a section on the line 16—16 of Fig. 14;

Fig. 17 is a section on the line 17—17 of Fig. 14;

Fig. 18 is a fragmental elevation of a portion of the main shell before a tool operating attachment has been connected; and

Fig. 19 is a fragmental elevation of one of the guiding rods of the guide for the Kirschner wire illustrated in Fig. 14.

In Fig. 1, there is shown a main shell 1 having attached thereto a handle 2. The shell 1 is provided to receive an electric motor 3 and equipped with a cover 4 positioned in place on the shell 1 by a bayonet slot connection 5.

The handle 2 in the present instance is equipped with an outlet plug 6 adapted to receive and stop shocks connected to a source of current not shown. The plug 6 has connected thereto the conductors 7 and 8. The conductor 7 is connected in the present instance, see Fig. 8 to the contact 9 and the conductor 8 connected to the conducting bar 10. The contact 9 and bar 10 as shown are connected to the support 11

30 having a second conducting bar 12. The conducting bar 12 has a contact 13 at one end and a spring contact arm 14 at the other end. This contact arm 14 of the bar 12 and the spring contact arm 15 of the bar 10 extend along one

35 face of the shell 1 to engage the two contact buttons 16 and 17 of the motor 3. The contact buttons 16 and 17, see Fig. 6, are positioned in an insulating plate 18 adapted to engage the inner faces of the ribs 20 and 21 of the shell 1,

40 thereby to position the buttons 16 and 17 in contact connecting position with the spring arms 14 and 15.

As shown, the shell 1 is also preferably provided with the ribs 22 and 23 to center the motor

45 3 relative to the shell 1 so that its shaft 24 and the pins 25 may be positioned to receive the slots of the intermediate connecting pieces hereinafter to be described.

The contacts 9 and 13 are normally open and 50 adapted to be closed by engaging the contact

points 26 and 27 of the movable U-shaped conductor 23 mounted on the trigger 29 pivotally connected to the handle 2 by the shaft 33 and normally positioned with the contacts 26 and 27 spaced from the contacts 9 and 10 by the spring 31.

The motor 3 is preferably reversible having the four contacts 32, 33, 34 and 35, the contacts 32 and 33 as one pair and the contacts 34 and 35 as another pair in one case being connected to one another and the contacts 33 and 34 as one pair and the contacts 35 and 32 as another pair in another position for reversing the motor by means of the conducting plates 36 and 37 attached to the cover 4 and operable by the winged handle 38.

For high speed working such as when a saw is to be operated or a Kirschner wire drill then preferably the extension 39 of the shell 1 has connected thereto an intermediate connecting device including a shell 40 on which there is rotatably mounted the intermediate shaft element 41 having slots 42 with cammed jaws to receive the pins 25 of the shaft 24 of the motor.

The intermediate shaft element has a similar set of slots 43 with similar cammed jaws. The intermediate shaft element 41 is further anchored to rotate in the shell 40 by the screw 44 extending through the extension 39 and the shell 40 and then into the annular slot 45 of the intermediate shaft element 41.

From the foregoing, it will be seen that the intermediate shaft element 41 will normally rotate with the shaft 24 of the motor. On the other hand, when the motor is at rest and it is desired to anchor the intermediate shaft element 41 against rotation, the stop 46 is provided which extends through the extension 39 and shell 40 but is normally retained out of engagement with the intermediate shaft element 41 by the spring 47. Its inner end, however, is adapted to be pressed, into engagement with one of the slots 42 to anchor the same against rotation when certain adjustments or assemblies are to be made hereinafter to be described.

The shell 40, see particularly Fig. 18, is provided with cam slots 43 to receive suitable pins for connecting the shell 40 to the tool to be operated. In the case of the saw illustrated in Fig. 1, the cams 48 receive the pins 49 in the connecting ring 50 rotatably mounted on the cylindrical holder 51 through which extends the spindle 52 of a shaft which is connected by pins 53 which engage the slots 43 of the intermediate connecting member 41. The shell 51 is fixed to the block 54 by the pin 55, which block 54, see Fig. 2, consists of two cheek plates 56 and 57 forming an enlarged opening 53 for the collar member 58 and having a narrow longitudinally extending cylindrical chamber extending therefrom to receive the outer portion 59 of the spindle provided with a worm 61 in mesh with the worm wheel 62 rotatably mounted in the chamber 63 at the outer end of the block 54 formed by the plates 56 and 57.

Through the worm wheel there extends a screw member having a diminished portion 64 with an enlarged right hand threaded portion 65 to one side and an enlarged left hand threaded portion 66 on the other side. In the present instance, the portion 65 is integral with the diminished portion 64 and the portion 66 is secured to the diminished portion 64. The portion 64 is rotatably mounted in the worm wheel 62. Preferably as shown, the exposed end of the threaded portion

65 is provided with a keyway for the reception of a key whereby the threaded portions 65 and 66 may be rotated at any time. The threaded portions 65 and 66 are provided to receive and position the rotary saws 67 and 68 when two saws are used or to position a single saw, as for instance the saw 67 see Fig. 3 and a protection cap 69. The saws 67 and 68 when both are used are conformed to be mounted as a set, the saw 67 having a hub 70 secured thereto and the hub 70 provided with a pin 71, a pin receiving orifice 72 and an internally threaded opening 73 to receive the threaded portion 65 and the saw 68 is provided with a similar hub 74, the hub 74 having a pin 75, a pin receiving opening 76, and an internally threaded chamber 77 to receive the threaded portion 66. The worm wheel 62 is provided with two pin receiving openings 78 and 79, the opening 78 alining with the opening 72 of the hub 70 and with the pin 75 to receive the same as shown in Fig. 2 when the openings 79, 76 will be in alinement to receive the pin 71.

By means of the key 80 to be inserted in the keyway 81, it will thus be seen that the screw member containing the threaded portions 65 and 66 may be turned either to mount the saws 67 and 68 close to one another as shown in Fig. 2 or at any number of desired distances apart depending upon the length of the combined hubs 70 and 74 and the intermediate portion 32 of the worm wheel 62.

It will be noted that the ring 50 preferably has three projections 83 as particularly shown in Fig. 17 by the projections 84, 85 and 86 of the locking ring 87 there shown to facilitate rotating the ring 50 especially when the operator's hands are covered by surgeon's gloves and wet.

When a single saw is to be used, as an instance, the saw 67, see particularly Fig. 3, it is preferable to provide a protecting cap, such as the cap 69 illustrated in Fig. 3 to prevent the admission of any gauze or other material used in the operation. For this purpose the cap 69 is substantially identical to the hub 74 of the saw 68 with the exception that it is not equipped with a saw.

In Fig. 14, the slots 43 of the intermediate portion 41 receive the pins 88 of the spindle 89 which is rotatably mounted in the chambered block 90. For securing the chambered block to the extension 40 a pin 91 is provided in the ring 27. By manipulation of the projections 84, 85 and 86, the pin 91 may be moved over into the innermost position of the cam slot 43 for anchoring the block 90 to the extension 40.

Preferably as shown, when the spindle 89 is intended directly to engage the tool to be manipulated, there will be provided integral with the spindle 89 a chambered extension 92 having an external screw thread 93 to receive the clamping nut 94. The extension 92 is conformed to receive in the present instance three jaw elements 95 having cam faces 96 to cooperate with the inner cam faces of the clamping nut 94 and to receive between the three jaws 95 the drilling rod 97 or other drilling tool. The drilling rod in the present instance is shown as typical of the well known Kirschner bone drilling wire.

Since the length of the Kirschner wire 97 is not infrequently very considerable, in order to support the same while it is being rotated in the act of drilling, the supporting device now to be described is provided.

This supporting device consists essentially of three equally spaced cylindrical elements 98, 99 and 100 formed on the block 90 which are

adapted to receive the outermost telescoping cylinders 101, three in number secured to the bracket 102, which telescoping elements 101 in turn are adapted to receive the three telescoping elements 103 secured to the bracket 104 which in turn are adapted to receive the three telescoping elements 105 secured to the brackets 106 and 107. The brackets 102, 104, 106 and 107 are in addition provided with a central orifice to receive the drilling wire 97, see for instance 10 the orifice 108 in the bracket 106.

In order to frictionally anchor the guiding rods 105 in the guiding elements 103 and in turn the guiding elements 103 in the guiding elements 101 preferably, see Fig. 19, slots are 15 formed as an instance the slots 109 and 110 with intervening tongue 111 depressed resiliently to engage a rod element 105 and similarly the elements 101 provided with slots 112 and 113 with an intervening tongue 114 depressed resiliently to engage a guiding element 103.

The present invention also aims to reduce the parts in a surgeon's kit to a minimum and for this reason shows a reducing element which may be attached to the shell 1 for operating, as an instance, a slow turning binding screw for binding two bone elements such as the elements 115 and 116 to one another. In the present instance, there is shown as attached to the reducing element the screw 117 which has a tapered end 118 and an angular head 119 to be gripped by a tool holder 120 having a spring finger 121 frictionally to engage one side of the angular head 119. The tool holder 120 has a spindle 122 which may be connected to the driven shaft 123 by any suitable means, such for instance as the intermediate element 223 having recesses to receive pins on the shaft 123, such as the pins 25 on the shaft 24 and the locking nut 124 provided to secure locking jaws to the spindle 122 such as the locking jaws 95, in which case the intermediate element 223 is journaled in the bearing 125 supported by the end wall 126 of the auxiliary shell 127, while the shaft 123 is preferably journaled as shown in the partitions 128 and 129.

On the shaft 123, there is fixed in the present instance, the gear 130 in mesh with the small gear 131 on the shaft 132, which shaft 132 is journaled in the partitions 128 and 129. On the shaft 132, there is fixed the large gear 133 in mesh with the small gear 134 on the shaft 135 also journaled in the partitions 128 and 129. On the shaft 135, there is fixed the large gear 136 in mesh with the small gear 137 fixed on the shaft 138 also journaled in the partitions 128 and 129.

On a portion of the shaft 138 extending between the partition 128 and the end wall 126, there is fixed the large gear 139 in mesh with the small gear 140 fixed on the shaft 141 journaled in the block 142 and the partition 123. The inner end of the shaft 141 is provided with pins 143 to receive the slots 144 of the intermediate connecting member 145 provided with slots 146 to receive the pins 25 on the shaft 24 of the motor 3.

The shell 127 is provided with a bayonet slot 147 to receive the pin 148 on the shell 1 and thus lock it in position.

The handle or grip 2, as particularly shown in Fig. 1 is preferably positioned well beneath the center of gravity of the instrument to facilitate balancing the same so necessary in the easy operation of the instrument.

Preferably also, see the direction of the teeth 150 of the saw 62 in Fig. 1, when rotating in the direction of the arrow 151, the saw will tend to throw the bone dust or other anatomical matter out of the field of vision of the operator. The saw attachment shown in Fig. 1 is of course intended mainly for bone grafting operations where the incision in the flesh to accommodate the saw may be reduced to a minimum and merely sufficient to receive the saw, either a single blade or double blade as the case may be. In other words, with this attachment, it will not be necessary to extend the width of the incision to provide space for manipulating the instrument as is the case with the ordinary instruments heretofore used.

It will also be apparent with this instrument that when the two blades are used and after two parallel cuts have been made in a bone, that 20 one of the blades can be quickly removed as an instance the blade 68 and the cap 69 thereupon secured in place and then the ends of sections of bone so defined cut by the single blade and the section or sections quickly slid along the groove so formed in a minimum period of time.

Furthermore, it will also appear that if the operator should then wish entirely to remove the saw attachment and replace it with another attachment, the projections 83 will facilitate loosening the saw attachment and securing another attachment in place thereof, the projections accommodating themselves readily to the slippery gloved fingers of the attendant or operator so that the removal and substitution 30 can take place in the shortest interval of time possible.

Positively to prevent the saw from turning with the shaft 52, the abutting ends of the shells 51 and 40 are provided with cooperating projections and notches 152, preferably four in number.

40 The screw 117 is formed to facilitate movement of the same in a predetermined straight line. As an instance, the end 118 is provided with a centrally located point 153 from which the screw tapers outwardly into the tapered portion 118 to the main body portion with a very gradual incline to the thread approximating forty-five degrees to the axis of the screw. This screw 117 as shown in Fig. 10 is intended to be left in the bone until the fractured pieces have knit and in some cases is left there permanently.

45 In view of the foregoing, after the drill attachment shown in Fig. 9 has turned the screw 117 into place, the spring lip 121 comes into play, it then only being necessary to frictionally slip the spindle 122 from the screw head 119 and leave the screw 117 in the bone. In some cases, it may be desirable to remove the screw 117 after the bone portions have become knit. Then it will only be necessary to make a small incision to expose the head 119 and then frictionally slip the spindle 122 into place, set the motor for reverse movement by turning the wing elements 38 to register with the mark "L" and then press the trigger 29 in the regular way and the screw will be rotated in the reverse direction and removed.

70 The reduction unit used when a screw, such as the screw 117 is to be secured in place or removed has already been explained, the reduction in revolutions per minute being approximately from sixteen thousand R. P. M. to one hundred R. P. M. which is reduced to eighty

R. P. M. under load whereby any boring or drilling action will be effectively avoided and the screw merely cut itself into a locking position in the bone. Obviously since the screw 117 is intended to be left in the bone tissue, it is desirable to produce these screws from non-oxidizing metal, such as stainless steel or the like.

When the wire drill is used, it is particularly desirous to have the wire 97 drill through a bone in a perfectly straight path since experience has taught that in such cases the accompanying pain to the patient when traction is made may be reduced to a minimum if not entirely eliminated. With the present guiding elements 101, 103 and 105 and the combination motor holder and instrument attachment, the operating surgeon is merely called upon to hold the motor steady after making contact. After the wire 97 has so been drilled through the bone, the ordinary Kirschner horse-shoe clamp may be used to maintain the wire stretched in a straight line and then the weight attached to the horse-shoe clamp in the usual way.

Before the horseshoe clamp aforesaid is attached in order to remove a wire 97 from the drilling attachment in some instances, the same is cut off leaving a small portion in the drilling attachment. In other cases, the guiding elements 101, 103 and 105 are moved away from the shell 1 to clear the ring 87 whereupon the projections 84, 85 and 86 are engaged and turned. To prevent the wire 97 from turning during this procedure, the motor 3 is first shut off and then the stop pin 48 engaged and pressed to enter one of the slots 42 whereupon the ring 89 can with facility be turned, and thereupon the guiding elements 101, 103, 105 and wire drill attachment removed whereupon the clamping nut 94 can be turned to release the jaws 95 or else the nut 94 turned to release the jaws 95 before the ring 87 is turned.

Preferably the motor 3 has a cylindrical housing 154 having a diminished cylindrical portion 155 conformed to fit snugly in the ring 156 having an annular flange secured to the inner end of the shell 1 concentric with the opening formed by the diminished projection 39. When the motor 3 is positioned with its diminished end 155 locked in the ring 156, the motor 3 is resiliently locked in such position by the cover 4 due to the spring fingers 157 formed thereon and engaging the rear end 158 of the motor 3, see Figs. 1, 6 and 7.

It is obvious that various changes and modifications may be made to the details of construction without departing from the general spirit of the invention as set forth in the appended claims.

I claim:

1. In a surgical instrument, the combination of a main shell having a cylindrical projection for receiving an electric motor with its shaft protruding into said projection, a block, means for removably connecting said block to said projection, a second shaft in said block and operatively associated with the motor shaft, a worm on said second shaft, a bearing at the outer end of said block, worm wheel shaft elements journaled in said bearing, a worm wheel fixed to said worm wheel shaft elements and in mesh with said worm, hubs on said worm wheel shaft elements, and a pair of rotary saws removably connected to the opposite ends of said hubs for sole or joint use.

2. In a surgical instrument, the combination

of a main shell having a cylindrical projection for receiving an electric motor with its shaft protruding into said projection, a block, means for removably connecting said block to said projection, a second shaft in said block and operatively associated with the motor shaft, a worm on said second shaft, a bearing at the outer end of said block, worm wheel shaft elements journaled in said bearing, a worm wheel associated with said worm wheel shaft elements and in mesh with said worm, hubs on said worm wheel shaft elements, a pair of rotary saws removably connected to said hubs on opposite sides of said worm wheel, and means for adjusting the spacing of said saws relative to one another.

3. In a surgical instrument, the combination of a main shell having a cylindrical projection for receiving an electric motor with its shaft protruding into said projection, a bearing removably connected to said projection, a second shaft in said bearing, an intermediate connecting shaft element in said bearing operatively associating said second shaft with the motor shaft, a split block secured to the end of said bearing and having a chamber, a worm on the end of said second shaft, a worm wheel shaft journaled in said chamber, a worm wheel mounted on said worm wheel shaft and in mesh with said worm, a rotary saw having an internal screw threaded hub and an axially extending pin, there being a pin opening in said worm wheel to receive said pin, and a stem extending through said worm wheel and having a screw threaded portion thereon to receive the screw threaded portion of said hub.

4. In a surgical instrument, the combination of a main shell having a cylindrical projection for receiving an electric motor with its shaft protruding into said projection, a bearing removably connected to said projection, a second shaft in said bearing, an intermediate connecting shaft element in said bearing operatively associating said second shaft with the motor shaft, a split block secured to the end of said bearing and having a chamber, a worm on the end of said second shaft, a worm wheel shaft journaled in said chamber, a worm wheel on said worm wheel shaft and in mesh with said worm, a pair of rotary saws having internally screw threaded hubs and axially extending pins and pin openings, there being pin openings in said worm wheel to receive said pins, a stem extending through said worm wheel and having a right hand screw threaded portion on one end and a left hand screw threaded portion on the other end to receive the screw threaded portions of said hubs and thereby facilitate spacing the saws from one another the required distance, and a key receiving opening in an end of said stem to facilitate turning said stem.

5. In a surgical instrument, the combination of a main shell having a cylindrical projection for receiving an electric motor with its shaft protruding into said projection, a bearing removably connected to said projection, a second shaft in said bearing, an intermediate connecting shaft element in said bearing operatively associating said second shaft with the motor shaft, a split block secured to the end of said bearing and having a chamber, a worm on the end of said second shaft, a worm wheel shaft journaled in said chamber, a worm wheel mounted on said worm wheel shaft and in mesh with said worm, a rotary saw and a cap having internally screw threaded hubs and axially extending pins and pin openings to receive the pins of one another,

there being pin openings in said worm wheel to receive said pins, and a stem extending through said worm wheel and having a right hand screw threaded portion on one end and a left hand screw threaded portion on the other end to receive the screw threaded portions of said hubs and thereby facilitate securing both saw and cap in position.

6. In a surgical instrument, the combination of a bearing, a motor-driven shaft mounted in said bearing, a worm on said shaft, a worm wheel shaft journaled in the outer end of said bearing, a worm wheel mounted on said worm wheel shaft and in mesh with said worm, a pair of rotary saws removably connected to said worm wheel on opposite sides of said worm wheel, and means for adjusting the spacing of said saws relative to one another.

7. In a surgical instrument, the combination of a bearing, a motor-driven shaft journaled in said bearing, a split block secured to the end of said bearing and having a chamber, a worm on the end of said shaft, a worm wheel shaft journaled in said chamber, a worm wheel on said worm wheel shaft and in mesh with said worm, a rotary saw having an internal screw threaded hub and an axially extending pin, there being a pin opening in said worm wheel to receive said pin, and a stem extending through said worm wheel and having a screw threaded portion thereon to receive the screw threaded portion of said hub.

8. In a surgical instrument, the combination of a bearing, a motor-driven shaft mounted in said bearing, a split block secured to the end of said bearing and having a chamber, a worm on the end of said shaft, a worm wheel shaft journaled in said chamber, a worm wheel mounted on said worm wheel shaft and in mesh with said worm, a pair of rotary saws having internally

5 screw threaded hubs and axially extending pins and pin openings, there being pin openings in said worm wheel to receive said pins, a stem extending through said worm wheel and having a right-hand screw threaded portion on one end and a left-hand screw threaded portion on the other end to receive the screw threaded portions of said hubs and thereby facilitate spacing the saws from one another the required distance, and a key receiving opening in an end of said stem to facilitate turning said stem.

10 15 20 25 30 35 40 In a surgical instrument, the combination of a bearing, a motor-driven shaft journaled in said bearing, a split block secured to the end of said bearing and having a chamber, a worm on the end of said shaft, a worm wheel shaft journaled in said chamber, a worm wheel mounted on said worm wheel shaft and in mesh with said worm, a rotary saw and a cap having internally screw threaded hubs and axially extending pins and pin openings to receive the pins of one another, there being pin openings in said worm wheel to receive said pins, and a stem extending through said worm wheel and having a right-hand screw threaded portion on one end and a left-hand screw threaded portion on the other end to receive the screw threaded portions of said hubs and thereby facilitate securing both saw and cap in position.

10. In a surgical instrument, the combination of a shell, a motor-driven shaft mounted in said shell, a worm on said shaft, a bearing at the outer end of said shell, worm wheel shaft elements journaled in said bearing, a worm wheel associated with said worm wheel shaft elements and in mesh with said worm, hubs on said worm wheel shaft elements, and a pair of rotary saws removably connected to said hubs on opposite sides of said worm wheel for sole or joint use.

SAMUEL LLOYD FISHER.
